APPLICATOR

Leon A. Spilo, New York, N. Y., assignor to Clairol Incorporated, New York, N. Y., a corporation of Connecticut

Application August 21, 1952, Serial No. 21,142

Term of patent 14 years

(Cl. D9—2)

To all whom it may concern:

Be it known that I, Leon A. Spilo, a citizen of the United States, residing at 20 West 86th Street, city, county, and State of New York, have invented a new, original, and ornamental Design for an Applicator, of which the following is a specification, reference being had to the accompanying drawing forming a part hereof, in which

Fig. 1 is a front elevation of an applicator showing my new design.

Fig. 2 is an end elevation of the same.

Fig. 3 is a plan view looking down along lines 3—3 of Fig. 1.

Fig. 4 is a plan view of the same looking up. The dotted line showing of a bottle in Fig. 1 is for illustrative purposes only.

I claim:

The ornamental design for an applicator, as shown and described.

LEON A. SPILO.
